[57] CLAIM

The ornamental design for an inflow water treatment adapter for chemical toilets, as shown and described.

DESCRIPTION

FIG. 1 is a left front perspective of an inflow water treatment adapter for chemical toilets, showing our new design;

FIG. 2 is a side elevational view, the opposite side elevational view being substantially a mirror image, thereof;

FIG. 3 is a top plan view, thereof;

FIG. 4 is a bottom plan view, thereof;

FIG. 5 is an elevational view of one end, thereof; and,

FIG. 6 is an elevational view of the other end.

FIG. 1.

FIG. 2.

FIG. 3.

FIG. 4.

FIG. 5

FIG. 6.
